(57) **CLAIM**

The ornamental design for a light as shown and described.

DESCRIPTION

FIG. 1 is a top perspective view of a light, showing our new design.

FIG. 2 is a bottom perspective view.

FIG. 3 is a front view.

FIG. 4 is a rear view.

FIG. 5 is a right-side view.

FIG. 6 is a left-side view.

FIG. 7 is a top view; and,

FIG. 8 is a bottom view.

Portions of the light are shown in broken lines. Portions shown in broken lines form no part of the claimed design. The downrod is shown with a zig-zag break line in its length. The appearance of any portion of the Light between the Zig-Zag break lines forms no part of the claimed design.
